UNITED STATES PATENT OFFICE

FRANK ELLISON BEST AND FREDERICK POWELL, OF SEATTLE, WASHINGTON; SAID POWELL ASSIGNOR TO FRANK E. BEST, INC., OF SEATTLE, WASHINGTON, A CORPORATION OF WASHINGTON

MORTISE DEAD LOCK

Application filed October 2, 1924. Serial No. 741,172.

Our invention relates to improvements in mortise dead locks and the object of our invention is to provide a mortise dead lock having a latch bolt that is operable from the inside by a thumb turn, the lock being constructed so that the thumb turn may be selectively positioned to lock the latch mechanism so that it can not be unlocked by the insertion of a key in the lock from the outside or to leave the latch mechanism free to be operated by the insertion of a key in the lock from the outside.

Other objects are to provide a mortise dead lock of simple and efficient construction that is not expensive to manufacture and that is comparatively easy to install on a door.

Other and more specific objects will be apparent from the following description taken in connection with the accompanying drawings.

In the accompanying drawings, Figure 1 is a sectional view on broken line 1—1 of Fig. 2 of a mortise dead lock constructed in accordance with our invention.

Fig. 2 is a sectional view of the same substantially on broken line 2—2 of Fig. 1, parts being shown in elevation.

Fig. 3 is a sectional view of the same substantially on broken line 3—3 of Fig. 2.

Figs. 4, 5, 6 and 7 are isometric views of details of the invention.

Figs. 8 and 9 are somewhat diagrammatic detached views illustrating the operation of the locking devices.

Fig. 10 is a detached perspective view of a bushing and hub member embodied in the invention.

Like reference numerals designate like parts throughout the several views.

Referring to the drawings 10 designates a door bored inwardly from the front edge to form a cylindrical cavity 11 for the reception of a tubular latch housing 12 and bored through from one side to the other to form a tubular passageway 13 wherein a cylindrical lock housing 14 may be inserted, the center of the transverse passageway 13 being substantially tangent to the lowermost portion of the cavity 11.

The lower half of the latch housing 12 is

cut away at the rear end to afford clearance for the lock housing 14. In assembling, the lock housing 14 is inserted first and the latch housing 12 is afterwards inserted and is secured within the cavity 11 by a face plate 16 which is made fast, by screws 17, to the edge of the door. The latch housing 12 is preferably permanently secured to the face plate 16 and said face plate may be mortised into the edge of the door when installed. The top of the lock housing 14 is cut away as at 15.

18 is a bolt, reciprocably supported in the face plate 16, and having a rearwardly extending shank 19, of smaller cross sectional size provided in its upper edge, near the rear end with two locking notches 20 and 21 and provided in its lower edge near the rear end with an arcuate notch 22 having inclined approaches 23 and adapted to receive bolt moving means. The rear end of the bolt shank 19 is further notched on the bottom edge as at 24 by cutting away one corner thereof to afford clearance for certain parts hereinafter described, the forward end of notch 24 being curved downwardly as at 25 where it intersects the arcuate notch 22. The rear end of bolt shank 19 extends through the cut away portion 15 of lock housing 14.

26 is a locking member secured by a pivot 27 to an indented portion 28 on the side of latch housing 12 and having a locking lug 29 on its inner end that is arranged to selectively lock within the notches 20 or 21 in the bolt shank 19 to hold said bolt shank in a projected or retracted position. A spring 30 secured to lug 29 yieldingly urges such lug into engagement with the bolt shank 19. The bottom edge of the locking member 26 is relieved or cut away on curved lines as at 26' for purposes hereinafter explained.

The lock housing 14 contains a pin tumbler lock 31 removably locked within said housing 14 by key operated means and having a rotatable key plug, not shown, upon the inner end of which is a throw member 32 from which projects a pin 33.

A tubular bushing 35 is arranged to fit snugly within the rear end of lock housing 14 and seat against a shoulder 34 and the

extreme rear end of the housing is crimped over the bushing as at 39 to hold the bushing in the housing. The bushing 35 has an inner end or hub 36 of reduced diameter upon which the inner end of the bolt shank 19 and locking member 26 are arranged to rest, the hub 36 preferably being flattened slightly on the top side.

Screws 37 extending through a face plate 38 on the inner side of the door and threaded into the bushing 35 hold the lock housing 14 in assembled position in the door.

40 is a bolt operating member arranged to fit rotatably within bushing 35 and having on its outer end a head 41 of peculiar shape which has two spaced apart prongs 42 projecting in one direction and a lug 43 projecting in the opposite direction. A stud pin 44 extends inwardly from lug 43 for lifting the locking member 26 and moving the bolt 18 as hereinafter explained. A hole preferably square, 45 extends lengthwise through bolt operating member 40 concentric with the axis thereof. A square shank 46 is arranged to fit within square hole 45 and is secured to a thumb turn 47 that is rotatably mounted in face plate 38.

The inner surfaces of the prong members 42 are cut away or rounded out as at 48 to facilitate the operation of throw pin 33.

In the operation of the lock, rotation of the lock operating member 40 will first cause pin 44 to lift locking member 26 so the lug 29 is clear of notches 20 or 21 and to then engage within notch 22 and move bolt 18.

A spring collar 50, Fig. 4, is arranged to fit over the hub 36 on the end of bushing 35 and has inwardly bent hook members 51 arranged to snap into recesses in said hub. The collar 50 is provided with two outwardly bent lugs 52 and 53 arranged to be engaged by the stud pin 44 to form positive stops and is further provided with resilient or yielding detents 54 and 55 against which the pin 44 may strike and over which such pin 44 may ride, the detents 54 and 55 ordinarily serving as stops for pin 44 but being shaped so that the pin 44 may be caused to ride thereover by exerting excessive torque on thumb turn 47.

In the operation of the lock, when the bolt is projected outwardly the head 41 of the lock operating member will, under ordinary operating conditions, be stopped in the position shown in Fig. 2 with the pin 44 resting against the detent 54. From this position the lock operating member may be turned in a clockwise direction to retract the bolt 18 by inserting a key in lock 31 and turning the throw member 32 and pin 33 to the right, the pin 33 starting from a position coaxial with lock operating member 40 and describing an arc, see dotted lines Figs. 8 and 9, about center 56 engages left hand prong 42 and turns the lock operating member into the position shown in Fig. 8, thence continues to its orig-

inal position coaxial with lock operating member 40 to permit withdrawal of the key from the lock. In a similar manner the lock operating member may be moved from the retracted position, Fig. 8, to the locking position, Fig. 2, by turning the key to the left. The lock operating member may always be turned by turning the thumb turn 47. If it is desired to set the lock so that it can not be retracted by use of the key from the outside sufficient torque may be exerted on thumb turn 47 to cause the pin 44 to ride over the detent 54 and turn the bolt operating member 40 from the position shown in Fig. 2 to the position shown in Fig. 9, in which latter position any attempt to turn throw pin 33 will cause it to strike the walls of square opening 45 and be stopped thereby without exerting any force capable of rotating the lock operating member. This makes it possible for a person on the inside to lock the door either so that it can be opened with a key by a person on the outside or so that it can not be opened at all by a person on the outside.

The foregoing description and accompanying drawings clearly disclose a preferred embodiment of our invention but it will be understood that this disclosure is merely illustrative and that such changes may be resorted to as are within the scope of the following claims.

We claim:

1. In a door lock of the class described a latch bolt, a rotatably mounted member arranged to engage with and move said latch bolt, a thumb turn on one side of the door, arranged to turn said rotatably mounted member, and a key operated lock on the other side of the door having throw means arranged to turn said latch bolt operating member when it is set in one position but inoperative to turn said latch bolt operating member when it is set in another position.

2. In a mortise dead lock of the class described, the combination with a door having a hole bored inwardly from one edge and another hole bored crosswise thereof, the center of said last named hole being substantially tangent to the periphery of said first named hole, latch housing in said first named hole, latch mechanism therein, a lock housing in said last named hole and mechanism in said lock housing for operating said latch bolt.

3. In a lock of the class described a rotatable latch bolt operating member having a head provided with a substantially U shaped radial slot extending from the center outwardly and a key operated lock having a throw pin movable in an arc substantially tangent to the axis of said latch bolt operating member and projecting into said slot said latch bolt operating member being arranged to be moved by said pin from certain positions but being incapable of being moved by said pin from other positions.

4. In a lock of the class described a latch lock and a latch bolt locking member arranged to be released by said latch bolt operating member.

FRANK ELLISON BEST.
FREDERICK POWELL.

70

5 bolt, a rotatable latch bolt operating member arranged to operate said latch bolt and having an axial perforation therein, a head on one end of said latch bolt operating member

5 said head having a slot extending radially from the center outwardly, a thumb turn connected with one end of said latch bolt operating member and a lock having a throw pin movable in an arc that passes through the

10 axis of said latch bolt operating member and arranged to project into said slot.

5. In a lock of the class described a latch bolt having a notch in one edge thereof, a latch bolt operating member mounted for rotation and having means for engaging within the notch in said latch bolt for moving the same, said latch bolt operating member having a slot in one end, one end of the slot being substantially on the central axis of said latch bolt operating member, a lock on the outer side of said door said lock having a throw pin movable in an arc that passes through the axis of rotation of said bolt operating member and that projects into said slot and a thumb turn on the inner side of said door for turning said bolt operating member.

6. In a lock of the class described, the combination with a door having a bore that extends inwardly from one edge and having a transverse bore intersecting said first named bore the center of said transverse bore being substantially tangent to the periphery of said first named bore, a latch housing arranged to fit within said first named bore, a lock housing arranged to fit within said last named bore, a latch bolt in said latch housing, said latch bolt having a notch in its bottom edge, a latch bolt operating member embodying a rotatably mounted shank having a longitudinally extending hole of square cross section, a head on said shank, a bolt operating pin secured to said head and extending inwardly along said shank in spaced relation therefrom, two spaced apart prongs on said head affording a U shaped slot diametrically opposite said pin, said slot terminating in said square hole, a bushing in said lock housing rotatably supporting said latch bolt operating member, a thumb turn for the inside of said door said thumb turn having a square shank that extends into said square hole, a key operated lock for the outside of said door said lock having a throw pin arranged to project into the U shaped slot in the head of said latch bolt operating member and movable in an arc that passes through the axis of said latch bolt operating member, said latch bolt operating member being arranged to be turned by said pin from two positions but being incapable of being turned by said pin from another position, detent means for permitting said latch bolt operating member to be selectively positioned by said thumb turn so that it may or may not be operated by said
